CLAIM

The ornamental design for a light assembly, as shown and described.

DESCRIPTION

FIG. 1 is a perspective view taken from above and from the side of the light assembly embodying our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an enlarged right side elevational view thereof;

FIG. 7 is an enlarged left side elevational view thereof;

FIG. 8 is an enlarged cross-sectional view of FIG. 3 taken along line A—A;

FIG. 9 is another perspective view taken from above and from the side of the light assembly with the lamp and the glue board assembly removed;

FIG. 10 is a front elevational view thereof; and,

FIG. 11 is a top plan view thereof.

Portions of the device are shown removed in FIGS. 9-11 for illustrative purposes only.
